UNITED STATES PATENT OFFICE.

EMIL L. SPRENGER, OF NEW KENSINGTON, PENNSYLVANIA.

LOCK FOR PINS.

No. 853,807.

Specification of Letters Patent.

Patented May 14, 1907.

Application filed November 16, 1906. Serial No. 343,692.

To all whom it may concern:

Be it known that I, EMIL L. SPRENGER, a citizen of the United States of America, residing at New Kensington, in the county of Allegheny and State of Pennsylvania, have invented certain new and useful Improvements in Locks for Pins, of which the following is a specification, reference being had therein to the accompanying drawing.

10 This invention relates to safety attachments for hat pins, scarf pins or like articles, and its object is to provide a pin with a detachable guard for preventing the withdrawal of the pin or its accidental displacement.

15 The construction of the improvement will be more fully described hereinafter in connection with the drawing which forms a part of this specification, and its novel features will be specifically pointed out in the appended claims.

20 In the drawing, Figure 1 is a side elevation of a hat pin with my improvement applied thereto, Fig. 2 is an elevation of the hat pin with the guard removed therefrom, Fig. 3 is a central longitudinal section of the pin attachment with its securing cap removed, Fig. 4 is a top plan view of the device shown in Fig. 3, Fig. 5 is a central longitudinal section of the removable cap of the attachment, and Fig. 6 is an elevation of the split ring employed to secure the removable cap of the device.

25 The reference numeral 1 represents the casing or body portion of the attachment which may be cylindrical, square or other shape in cross section and is formed with a central bore 2 to receive the pointed end of a hat pin 3. The upper portion 4 of the casing 40 is externally screw threaded and its upper end 5 is tapered and slotted to provide a plurality of clamping fingers 6. The casing is also formed with an annular groove 7 at a point above the termination of its screw threads to receive a split ring 8 of spring metal.

30 The reference numeral 9 designates a hollow internally threaded cap provided with a tapered end portion 10 provided with a central opening 11 through which the pin 3 extends. The cap 9 is also provided with an annular internal groove 12 of greater width than the width of the split ring 8.

35 The utility of the device constructed as thus described will be readily understood. After the pin 3 has been inserted through a

hat, the safety or guard attachment is applied to the pointed end of the pin, the cap 9 being screwed upon the threaded portion 4 of the casing only partially. The cap 9 is 60 screwed upon the threaded end 4 of the casing which brings the split ring 8 opposite the annular groove 12 in said cap. The ring 8 springs into the groove 12, and thus the cap is permanently locked upon the threaded end 65 of the casing. It, however, has a limited longitudinal movement thereon as the groove 12 is of greater width than that of the split ring as above stated. After the hat pin is inserted through the hat, the safety attachment is applied to the point end of the pin 70 after which the cap 9 is screwed down tightly which compresses the clamping fingers 6 upon the pin thus firmly securing the safety attachment in position thereon. It will be 75 apparent that a slight turning movement of the cap 9 will loosen it sufficiently to release the clamping fingers 6 to permit the attachment to be disengaged from the pin and allow the latter to be withdrawn.

80 The inner end of the bore 2 in the casing 1 is preferably formed with a contracted extension 13 to receive the sharpened point of the pin and prevent the latter from being bent or damaged. As illustrated in Fig. 1, 85 the outer end of the casing 1 may be ornamented or provided with a setting 14 to add to its ornamental appearance.

85 While the device is primarily designed as a safety attachment for hat pins it is equally well adapted for use as a guard or safety device for scarf pins. When the improvement is to be used as a scarf pin attachment it will of course be made of smaller size than when designed for attachment to a hat pin.

90 As illustrated in Fig. 2, a portion of the casing 1 and the adjoining portion of the cap 9 are externally knurled or roughened, as at 15 to facilitate the turning of the cap. Below its screw threads the casing 1 is preferably formed with an annular beveled shoulder 16 upon which fits the internally beveled end 17 of the cap 9, thus insuring a finished joint between the cap and casing.

95 What I claim and desire to secure by Letters Patent, is:—

1. A safety attachment for pins comprising a casing provided with a longitudinal bore and externally screw threaded and longitudinally split and tapered at one end to provide clamping fingers, and an internally threaded cap provided with a tapered end

2
having a pin opening therein, and means for permanently securing said cap upon the casing comprising a split ring, said cap being provided with an internal annular groove of greater width than said ring.

2. A safety attachment for pins comprising a casing formed with a longitudinal bore, and an annular external groove, and screw-threaded above and below said groove and having its upper end tapered and longitudinally split to provide clamping fingers, in combination with an internally threaded cap having a tapered upper end formed with a pin opening and an internal annular groove of greater width than the groove in the casing, and a split ring supported between said grooves.

3. A safety attachment for pins comprising a casing formed with a longitudinal bore having a contracted extension at its inner

end, and an annular external groove and being screw-threaded above and below said groove and having its upper end tapered and longitudinally split to provide clamping fingers, in combination with an internally screw-threaded cap tapered at its upper end and formed with a pin opening and provided with an annular internal groove of greater width than the groove in the casing and having its lower end beveled to snugly fit a beveled shoulder on the casing, and a split ring fitting the groove in the casing and adapted to project into the wider groove in the cap to permanently connect the cap and casing.

In testimony whereof I affix my signature 35 in the presence of two witnesses.

EMIL L. SPRENGER.
